CLAIM

The ornamental design for an plyometric box, as shown and described.

DESCRIPTION

FIG. 1 is a back perspective view of an plyometric box showing my new design;

FIG. 2 is a left side view thereof;

FIG. 3 is a right side view thereof;

FIG. 4 is a back view thereof;

FIG. 5 is a front view thereof;

FIG. 6 is a top view thereof;

FIG. 7 is a bottom view thereof; and,

FIG. 8 is a right side cross sectional view thereof, taken along line 8-8 in FIG. 6.

The broken lines in the Figures show portions of the exercise device which form no part of the claimed design.
